US0D1009826S

(12) **United States Design Patent** (10) **Patent No.:** **US D1,009,826 S**
(45) **Date of Patent:** **** Jan. 2, 2024**

(54) **HEADPHONES**

- (71) Applicant: **Austrian Audio GmbH**, Vienna (AT)
(72) Inventors: **Patrice Billaudet**, Markt Piesting (AT);
Philipp Schuster, Vienna (AT);
Bernhard Pinter, Moosbrunn (AT)
(73) Assignee: **AUSTRIAN AUDIO GMBH**, Vienna (AT)

(**) Term: **15 Years**

(21) Appl. No.: **35/516,046**

(22) Filed: **Nov. 2, 2022**

(80) **Hague Agreement Data**

- Int. Filing Date: **Nov. 2, 2022**
Int. Reg. No.: **DM/226040**
Int. Reg. Date: **Nov. 2, 2022**
Int. Reg. Pub. Date: **Jan. 20, 2023**
(51) **LOC (14) Cl.** **14-01**
(52) **U.S. Cl.**
USPC **D14/206**

Anton E. Skaugset

(57) **CLAIM**

The ornamental design for headphones, as shown and described.

DESCRIPTION

1. Headphones
- 1.1: Front perspective view
- 1.2: Front elevational view
- 1.3: Rear elevational view
- 1.4: Left side elevational view
- 1.5 Right side elevational view
- 1.6: Top plan view
- 1.7: Bottom plan view
- 1.8: rear perspective view

1 Claim, 8 Drawing Sheets
